(57) **CLAIM**

The ornamental design for a handheld semiconductor wafer handling tool, as shown and described.

DESCRIPTION

FIG. 1 is a top front perspective view of a handheld semiconductor wafer handling tool with a movable clip in a first position;

FIG. 2 is a front end view of the handheld semiconductor wafer handling tool of FIG. 1;

FIG. 3 is a back end view of the handheld semiconductor wafer handling tool of FIG. 1;

FIG. 4 is a right side view of the handheld semiconductor wafer handling tool of FIG. 1;

FIG. 5 is a left side view of the handheld semiconductor wafer handling tool of FIG. 1;

FIG. 6 is a top view of the handheld semiconductor wafer handling tool of FIG. 1;

FIG. 7 is a bottom view of the handheld semiconductor wafer handling tool of FIG. 1;

FIG. 8 is a bottom rear perspective view of the handheld semiconductor wafer handling tool of FIG. 1;

FIG. 9 is a top front perspective view of the handheld semiconductor wafer handling tool of FIG. 1 with the movable clip in a second position; and,

FIG. 10 is a perspective view of the handheld semiconductor wafer handling tool of FIG. 1 with a semiconductor wafer. The broken line portions of the semiconductor wafer handling tool in FIGS. 1 through 10 are not considered part of the claimed design. Additional broken lines in FIG. 10 are provided for purposes of environment and form no part of the claimed design.

1 Claim, 8 Drawing Sheets
